UNITED STATES PATENT OFFICE.

FRANK J. RUSSELL, OF NEW YORK, N. Y.

PLUG-SOCKET FOR ELECTRIC LAMPS, &c.

No. 818,791.

Specification of Letters Patent.

Patented April 24, 1906.

Application filed July 12, 1905. Serial No. 269,434.

To all whom it may concern:

Be it known that I, FRANK J. RUSSELL, a citizen of the United States, residing in the city of New York, borough of Brooklyn, county of Kings, and State of New York, have invented certain new and useful Improvements in Plug-Sockets for Electric Lamps, &c., of which the following is a specification sufficient to enable others skilled in the art to which the invention appertains to make and use the same.

My improvements relate to what are known as "sockets" for the reception of electric plugs for establishing electrical connections, as the plugs of incandescent electric lamps, extension circuit-plugs, and the like, and are designed to afford a simple structure in which the securing-screws, terminal screws, and wire-inlets are all accessible from the face or front of the socket through the lamp-plug holder, all the several screws being arranged longitudinally within and with relation to the socket as a whole and the use of all external or lateral screws being avoided. Hence my socket-piece may be installed in positions and places that would be otherwise inaccessible, as in corners and structures where lateral space is limited and insufficient to admit of the installation of the ordinary socket-piece with fastening-screws arranged at right angle to the axis thereof. For this reason I am also enabled to apply my socket to a "husk" or external shell without disturbing or parting the latter, so that said husks or external shells may be made integral and need not be split, perforated, or made into sections, as heretofore, in order to give access to laterally-arranged screws external to the socket. These and other advantages hereinafter enumerated I attain by my invention, which consists, essentially, in the construction and arrangement of parts herein described and claimed specifically, although I do not limit myself strictly to the identical configuration of parts shown, since certain modifications may be made therein without departing from the spirit and intent of my invention. For instance, the metallic plug-holder may be of the screw, spring-jaw, or any other form, according to the manufacture of plug or lamp to be accommodated, and a modified form of base may be used in applying the socket at right angles to tubular conduits, &c.

In the accompanying drawings, Figure 1 is

an elevation of my improved socket applied to a screw-nipple. Fig. 2 is a face or front view of the same. Fig. 3 is a longitudinal sectional elevation upon plane of line 3 3, Fig. 2. Fig. 4 is a similar view upon plane of line 4 4, Fig. 2. Fig. 5 is a similar view upon plane of line 5 5, Fig. 2. Fig. 6 is a rear end view showing the fixture-nipple in section. Fig. 7 is a rear view of the socket-body, shell, &c., the base being removed. Fig. 8 is a view of the inner face of the base-piece. Fig. 9 is a transverse section upon plane of line 9 9, Fig. 3; Fig. 10, a transverse section upon plane of line 10 10, Fig. 3; Fig. 11, a transverse section upon plane of line 11 11, Fig. 3. Fig. 12 is an elevation of the sleeve; Fig. 13, a longitudinal section upon plane of line 13 13, Fig. 12; Fig. 14, a longitudinal section of the sleeve upon plane of line 14 14, Fig. 13; Fig. 15, a front end view of the sleeve; Fig. 16, a rear end view of the sleeve; Fig. 17, an elevation of the core and plug-holder; Fig. 18, an elevation of the core and plug-holder, taken at right angles to Fig. 17; Fig. 19, a front end view of the plug-holder and core; Fig. 20, a rear elevation of the core with plug-holder attached, the cement filling being omitted. Fig. 21 is a section upon plane of line 21 21, Fig. 20. Fig. 22 is a section upon plane of line 22 22, Fig. 20. Figs. 23 and 24 are respectively front and rear views of the plug-holder detached. Fig. 25 is an elevation of the base-piece detached. Fig. 26 is a section of the same, taken upon plane of line 26 26, Fig. 8. Fig. 27 is a sectional elevation showing the application of my improved socket to the interior of a shell; Fig. 28, a similar view showing a modified form of attachment in which the socket-base is disconnected. Fig. 29 is a sectional elevation showing the application of my socket at right angles to a tubing-conduit; Fig. 30, a similar view taken at right angles to Fig. 29; Fig. 31, a face view of the modified form of base shown in Figs. 29 and 30; Fig. 32, a section upon plane of line 32 32, Fig. 31.

My socket consists, essentially, of four main parts—namely, the core C, formed of porcelain or other non-conducting material, the metallic plug-holder P, attached to the core, the inclosing sleeve S, and the base B.

The plug-holder P is cylindrical in general outline, its inner or rear end being formed with inwardly-projecting flanges p p, by which it is attached to the face of the core C by

2
 screws *a a*. As shown in the drawings, the cylindrical body of the plug-holder *P* is threaded for the reception of a screw-plug of an electric lamp, although, as before intimated, this is not material, since the metallic holder *P* may be formed and adapted to receive and retain any other form of plug. The flanges *p p* are formed with perforations *p' p'* to admit of the passage of the shanks of the screws *a a*, which also project through the holes *c c* and into rectangular recesses *c' c'*, formed in the back of the core for the reception of nuts *a' a'*, with which the screws *a a* engage. The holes *c c* and recesses *c' c'* are parallel to each other and to the axis of the core, and the heads of the screws *a a* are readily accessible through the plug-holder *P*. After the engagement of the screws *a a* with the nuts *a' a'* a filling of cement or other suitable material is applied to the recesses *c' c'* to insulate the ends of the screws and the nuts and hold the latter in position; but this filling does not prevent the rotation of the screws upon their axis when desirable, as for the purpose of utilizing one of these screws as a terminal binder, as shown in the drawings, by which means I dispense with the separate terminal contact-piece and terminal screw heretofore used, since my screw *a* holds the terminal wire *w* in direct electrical contact with one of the flanges *p* of the lamp-plug holder *P*, as will be seen by reference to Figs. 2, 3, and 9. The peripheral electrical contact with the lamp-plug *p* being thus provided for in a simple, effective, and economical manner, I next proceed in like manner to provide for the central electrical contact with the lamp or other plug, and this I accomplish by again dispensing with a special terminal contact-piece and by placing the terminal-wire-binding screw *D* centrally upon and within the core *C*, so that its head *d* affords an electrical contact-surface for engagement with the central contact of the lamp-plug *P*.

The threaded shank of the central binding screw *D* passes through an axial hole *c²* in the core *C* and engages with a nut *d'*, inserted in a rectangular recess *c³*, formed axially in said core for the reception and retention of the said nut, a filling of cement being likewise applied to said recess after the engagement of the screw and nut. The core *C* is also formed with an annular collar or flange *c⁴*, which surrounds the head of the terminal screw *D* when the latter is in position, except where the terminal wire *w'* is inserted between the screw-head and the core, at which point the latter is formed with a groove *c⁵*, through which the terminal wire extends. The annular flange *c⁴* lessens or obviates all danger of cross-contact or short-circuiting between the terminals and enables me to dispense with a mica disk or other form of insulation between the terminals.

The usual grooves or recesses *c⁶ c⁶* are formed in the back of the core *C* to accommodate the terminal wires, and said back portion of the core is also formed with the screw-holes *c⁷ c⁷*, the axes of which are parallel to the axis of the core *C*. The screw-holes *c⁷ c⁷* are flanked by shoulders *c⁸ c⁸*, which are countersunk in the core, so as to isolate the heads of the screws *e e*, by which the core *C* is secured to the base *B*.

The base *B* is formed with the threaded screw-holes *b b* for engagement with the screws *e e*. When designed for attachment to a nipple or threaded end *f* of a fixture, the threaded shank *b'* is split transversely to approximately one-half its diameter to form a jaw *b²*, by which the male screw on the nipple *f* may be pinched more or less by means of a set-screw *b³* for the purpose of securing the base *B* rigidly and positively in position. This method of utilizing the elasticity of the metal composing the shank of the base to lock the latter in position is preferable to the old method of using a set-screw impinging against the threaded portion of the nipple and at right angles thereto, in that the thread of the nipple is maintained intact and in condition for engagement with other socket-pieces, if desired, whereas by the use of a laterally-impinging screw the thread is injured or displaced to such an extent as to impair, if not prevent, its use for other socket-pieces.

The base *B* is formed with an annular shoulder *b⁴*, upon which the rear edge of the core *C* is seated, and with a cylindrical flange *b⁵* for the reception of the peripheral rear edge of the sleeve *S*. The sleeve *S* is provided with the usual lining *s*, of insulating material, and is of ordinary shape and construction, except that at its rear edge it is formed with inwardly-projecting tongues *s' s'*, which when the parts are assembled fit in behind the rear surface of the core *C*, which is formed with recesses *c⁹ c⁹* for their reception. The recesses *c⁹ c⁹* admit of a flush finish or bearing of the core upon the base and also lock the sleeve in position. The recesses *c⁶ c⁶* in the core made, as before stated, for the accommodation of the terminal wires are made sufficiently large to admit of the passage of these tongues *s' s'* on the sleeve, even when the terminal wires are in position, so that the core may be wired, if necessary, before the application of the sleeve *S*, although this is not material in practice, since the wiring, &c., can be done with almost equal facility after the sleeve is placed in position upon the core.

By the use of the lateral tongues *s' s'* on the sleeve I do away with the external set-screws heretofore made to extend at right angles through the cylindrical flange *b⁵* of the base through slots in the sleeve and into lateral recesses in the sides of the core, since in my construction the screws *e e* sustain all the parts in position. Hence the base *B* may

even be dispensed with if found expedient in applying the socket, and the latter, consisting in such cases of the core C, plug-holder P, and sleeve S, may be screwed to any suitable support, or where the socket is to be applied at right angles to a wire-conduit W, as in Figs. 29 and 30, screw-holes for the reception of the ends of the attaching-screws e e may be formed directly in said conduit W, and a base B' of modified construction may be used consisting of the cylindrical flange b⁵, formed with lips b⁶, fitting over the said conduit W. In either case the securing-screws e e perform, essentially, the same function.

15 It will be seen that by my construction and arrangement of parts I not only gain certain practical advantages in assembling and installing the parts, but I also simplify and cheapen the manufacture of the socket as a whole. For instance, special independently-formed terminal pieces are dispensed with, binding-screws alone being used to secure the terminal wires, and even one of the screws secures the plug-holder in position on the core 20 being used to effect electrical connection with said holder. Furthermore, the core of insulating material is so shaped as to constitute a "straight-draft" casting from which the mold may be withdrawn lengthwise, there being no lateral holes or recesses to complicate the dies and increase the cost of manufacture.

My socket is much more rigid and secure in position when installed as compared with those heretofore in use, because it is actually 25 and directly screwed to the base-piece or other support, whereas in the common form of socket the core is carried by a removable and portable sleeve, which is held to the base by bayonet-slots which engage lateral and 30 externally-exposed screws upon the base. An incidental advantage of my construction consists in the fact that the securing-screws are inclosed and protected from external interference, accidental or otherwise, so that 35 the integrity of the socket is insured and there is no danger of the parts working loose and apart from the supporting-base to be suspended upon the terminal wires, as frequently happens under present conditions. 40 Even the base-piece when used is secured to the fixture-nipple by a screw the head of which is isolated and protected by the socket when in position, so that it cannot be tampered with under ordinary conditions of use. 45 While having only an indirect bearing upon the present invention, it is still an important fact commercially that by my improvements I render it possible to simplify, cheapen the structure, and improve the appearance of 50 husks or like fixture-canopies, since each of such articles can now be made integral and the installation effected entirely through the opening thereof.

I have herein described my improved 55 socket as the receptacle for an electric-lamp

plug, although obviously any other similar electric plug may be used in connection therewith.

What I claim as my invention, and desire to secure by Letters Patent, is—

1. In an electric-plug socket such as designated, the combination of a core of non-conducting material formed with a central longitudinal screw-hole having a flange partly surrounding its outer end and terminating at 75 its inner end in an angular recess in the back of the core, said core being also formed with longitudinal screw-holes parallel to the axial screw-hole and also opening into angular recesses formed in the back of the core, a central terminal-wire-binding screw passing through said axial screw-hole with its head within the said flange on the outer end of the core and its inner end engaging with a nut in the central angular recess, a metallic plug- 80 holder formed with internal flanges and headed screws passing through said flanges and through the said parallel screw-holes in the core and engaging with nuts in the angular recesses formed in the back thereof, one of 85 said last-mentioned screws constituting a binder for the terminal wire with which the said metallic plug-holder is connected, whereby the heads of all three screws are accessible through said plug-holder.

2. In an electric-plug socket such as designated, the combination of a core of non-metallic material formed with a central longitudinal screw-hole and two screw-holes parallel thereto, all three screw-holes terminating in 100 angular recesses formed in the back of the core, said core being also formed with screw-holes parallel to the axis of the core whereby the latter may be secured to a base, and all of 105 said screw-holes being accessible through the plug-socket, said plug-socket formed with internal flanges, headed screws passing through said flanges and the core and engaging nuts in the recesses at the rear of the core, one of 110 said screws being utilized as a binder for the wire terminal with which the plug-socket is connected, and a central terminal-wire-binding-screw passing through said axial screw-hole and engaging with a nut in the central 115 recess formed in the back of the core, for the purpose described.

3. In an electric-plug socket such as designated, the combination of a plug-holder, a core of non-conducting material secured thereto, a base screw-holes formed in the core 120 parallel to the longitudinal axis of the socket screws passing therethrough and securing the core to the base, said screws being accessible, through the plug-holder, and said base formed with female screw-threads for engagement 125 with said securing-screws, for the purpose described.

4. In an electric-plug socket such as designated, the combination of a metallic plug-holder, a core of non-conducting material se- 130

2
cured thereto, a base screw-holes formed in the core parallel to the longitudinal axis of the socket, said screw-holes being countersunk to receive and surround the heads of the screws, screws passing therethrough and securing the core to the base, said screws being accessible through the plug-holder, and said base formed with female screw-threads for engagement with said securing-screws, for the purpose described.

5. In an electric-plug socket such as designated the combination of a metallic plug-holder formed with internal flanges, a core of non-conducting material formed with holes parallel to the longitudinal axis of the socket, headed screws passing through said internal flanges on the metallic plug-holder and through two of said longitudinal holes in the core and engaging with nuts situated in recesses formed for their reception in the core, said nuts, a base, securing-screws passing through other of said longitudinal holes in the core and securing it to the base, all of said screws being accessible through the plug-holder, and said base formed with female screw-threads for engagement with said securing-screws, for the purpose described.

6. In an electric-plug socket such as designated the combination with a metallic plug-holder, of a core of non-metallic material formed with a longitudinal axial screw-hole, a headed terminal-wire-binding screw extending through said axial screw-hole in the core and a nut at the rear of the core with which said screw engages, whereby the head of said central screw is utilized to bind a wire terminal and as a contact for the plug, substantially as set forth.

7. In an electric plug such as designated, the combination with the metallic plug-holder, of a core of non-conducting material formed with a longitudinal axial screw-hole opening at the rear into an angular recess formed in the back of the core and having its front end surrounded in part by concentric annular flange formed on the face of the core, a terminal-wire-binding screw extending through said axial screw-hole and a nut in the said central recess with which said screw engages, for the purpose described.

8. In an electric-plug socket such as designated, the combination of a metallic plug-holder formed with internal flanges, a core of non-conducting material formed with holes parallel to the longitudinal axis of the socket, headed screws passing through said internal flanges on the metallic plug-holder and through two of said longitudinal holes in the core and engaging with nuts situated in recesses formed for their reception in the core, said nuts, a wire-terminal-binding screw passing through a longitudinal hole formed in the axis of the core between the plug-holder flanges, and a nut in a central recess in said

core with which said central wire-terminal-binding screw engages, for the purpose described.

9. In an electric-plug socket such as designated, the combination of a metallic plug-holder formed with internal flanges, a core of non-conducting material formed with holes parallel to the longitudinal axis of the socket, headed screws passing through said internal flanges on the metallic plug-holder and through two of said longitudinal holes in the core and engaging with nuts situated in recesses formed for their reception in the core, said nuts, a wire-terminal-binding screw passing through a longitudinal hole formed in said core between the plug-holder flanges, a nut in a recess formed for its reception in said core with which said wire-terminal-binding screw engages, screws passing through other of said parallel longitudinal holes in the core and securing it to a base, and said base formed with female screw-threads for engagement with said securing-screws, for the purpose described.

10. In an electric-plug socket such as designated, the combination of a metallic plug-holder formed with internal flanges, a core of non-conducting material formed with holes parallel to the longitudinal axis of the socket, headed screws passing through said internal flanges on the metallic plug-holder and through two of said longitudinal holes in the core and engaging with nuts situated in recesses formed for their reception in the core, said nuts, a wire-terminal-binding screw passing through a longitudinal hole formed in the axis of said core, a nut in a central recess formed in said core with which said central wire-terminal-binding screw engages, screws passing through other of said parallel longitudinal holes in the core and securing it to a base, and said base formed with female screw-threads for engagement with said securing-screws, for the purpose described.

11. In an electric-plug socket such as designated, the combination with the plug-holder, of a core of non-conducting material formed with screw-holes and wire-inlet holes extending longitudinally with relation to the axis of the socket and accessible through the plug-holder, together with the securing and binding screws, for the purpose described.

12. An electric-plug socket such as designated, formed with a metallic plug-holder, and with a wire-terminal-binding screw extending longitudinally with relation to the axis of the socket, said binding-screw being accessible through the said plug-holder and constituting a central contact for the plug inserted therein, for the purpose described.

13. An electric-plug socket such as designated, formed with a central wire-terminal and contact screw, a flanged plug-holder screwed to the core of insulating material,

one of the screws by which the plug-holder is secured to the core constituting the other wire-terminal binder, and said core formed with a flange of insulating material interposed between the central contact and the flanges of the plug-holder for the purpose described.

14. In an electric-plug socket substantially such as designated, the combination with the metallic plug-holder, and the core of insulating material formed with securing - screw holes parallel to the longitudinal axis of the socket and accessible through the plug-holder, of a sleeve formed with inwardly-projecting tongues fitting in between the core and the base to which the latter is secured together with said base, for the purpose described.

15. In an electric-plug socket substantially such as designated, the combination with the metallic plug-holder, and the core of insulating material formed with securing - screw holes parallel to the longitudinal axis of the socket and accessible through the plug-holder, of a sleeve formed with inwardly-projecting tongues fitting in between the core and the base to which the latter is secured, said core being formed with recesses for the reception of said tongues whereby the sleeve

is locked in position for the purpose described 30 together with said base.

16. In an electric-plug socket substantially such as designated, the combination with the plug-holder, core and sleeve, of a base for attachment to the screw-nipple of a fixture, 35 said base being formed with a threaded shank for engagement with the fixture-nipple, the threaded shank being split transversely on one side to form a jaw which is threaded for engagement with a set-screw, together with 40 said set-screw, for the purpose described.

17. In an electric-plug socket substantially such as designated, the combination with the plug-holder, core and sleeve, of a base for attachment to the screw-nipple of a fixture, 45 said base being formed with a threaded shank for engagement with the fixture-nipple the threaded shank being split transversely on one side to form a jaw which is threaded for engagement with a set-screw, and said set- 50 screw arranged with its head bearing against the inner surface of the base for the purpose described.

FRANK J. RUSSELL
